UNITED STATES PATENT OFFICE.

FREDERICK HAGGER HEADLEY, OF NORTHFIELD, NEAR BIRMINGHAM, ENGLAND.

CHAIR CONSTRUCTION.

Application filed August 7, 1924, Serial No. 730,576, and in Great Britain January 12, 1924.

This invention relates to improvements in chair construction and consists of the matters hereinafter described and more particularly pointed out in the appended claims.

- 5 In chairs or stools and especially those embodying metallic legs wherein the bottom ends thereof are bent or otherwise arranged in substantially a horizontal plane to not only increase the spread or area thereof but 10 also to provide suitable feet therefor, it has been found difficult not only to finish off the ends of said feet but to apply casters or other antifriction members thereto so that the chair as a whole may be easily moved 15 about.

One of the objects of the present invention is to provide in a chair or stool a simple and efficient construction whereby the above mentioned difficulty is readily overcome.

- 20 A further object of the invention is to provide a novel arrangement of the parts whereby the spindle or shank of the caster is employed to secure the cap to the foot part of the leg in such a manner that said foot 25 part and cap, in turn, provides the bearing in which said spindle or shank is journaled.

These objects of the invention, as well as the many advantages thereof will more fully appear as I proceed with my specification.

- 30 In the drawings:—

Fig. 1 is a perspective view of a chair embodying my invention.

- Fig. 2 is a longitudinal vertical section, on an enlarged scale, through the foot part 35 of one of the legs of said chair.

Fig. 3 is a transverse vertical section through the same as taken on the line 3—3 of Fig. 2.

- Fig. 4 is a view similar to Fig. 2 showing 40 a modified form of construction.

The invention is herein illustrated and will be herein described as embodied in a metallic chair which includes a swivelling or rotative seat, but as is apparent the invention 45 is readily applicable to chairs and to stools made of other materials, where the peculiar features of construction make it advantageous to do so.

Referring now in detail to that embodiment of the invention illustrated particularly in Figs. 1 to 3 inclusive, of the accompanying drawings:—5 indicates, as a whole, the standard or support of a swivelling chair and 6 the seat thereof which includes in this 55 instance, a foldable back rest 7.

The standard 5 comprises, as shown in this instance, top and bottom vertically spaced bearing sleeves or collars 8 and 9, respectively, each of which has a plurality of arcuately spaced recesses or depressions to receive the 60 top ends of the leg members 10—10. Said legs are secured to said sleeves by means of bolts 11 which take through said legs and are threaded into said collars, suitable washers being interposed between said legs and the heads of said bolts. The bottom end of 65 said legs are bent to extend radially outward to terminate in substantially horizontally disposed feet 12 which increase the spread of the chair and its stability against tipping. 70

The seat, in this instance, carries a vertically disposed depending post 13 near its middle which has guided rotative bearing in the top collar or sleeve 8, and the bottom end of said post is threaded and engages in 74 a threaded hole in the bottom sleeve or collar 9, to provide the swivelling action for the seat 6, as is apparent.

The outer or foot end of each leg which, as shown herein, is tubular and therefore 80 normally open, is finished off to close the end thereof by a cap having a tubular body 14 which embraces or surrounds the end of said leg and an end wall 15 which closes the end of said tubular leg. Associated with each 85 foot or leg end is a caster or other antifriction device indicated as a whole by the reference member 16. Said caster, as herein shown, includes a bifurcated or forked frame 17 between the spaced arms of which an anti-friction element or caster wheel 18 is mounted in any suitable manner. Securely fixed to said fork frame is an upright or vertically disposed pintle or pin 19 which extends 90 through and has bearing in diametrically oppositely disposed, registering holes 20 and 21 in the leg end and cap respectively. On the top or cross bar of fork frame 17 and at the base of the pintle 19 is provided an annular bearing shoulder 22 to space said 95 fork from the cap when the caster has been applied to the chair leg. The pintle is of such a vertical length that its top end projects slightly above the body of the cap and to said projecting end is applied a washer 100 23 after which said end is upset to provide a head to secure the parts in position.

It will be apparent from the foregoing, that the pintle 19 passing, as it does, through the leg end and the body of the cap, will 110

lock said cap against dislodgement or removal and said leg end and said cap body by reason of the holes therein provide a substantial bearing in which the pintle is capable 5 of a rotative or turning movement. Thus, when the chair is moved about the floor on its casters, said casters will easily rotate about the pintles thereof so that said caster wheels will readily trail in the direction of 10 movement imparted to the chair.

In Fig. 4 I have illustrated a slightly modified form of the invention in this respect.

Instead of using a tubular cap, as before described, I may employ a cylindrical plug having 15 a body part 25 of a diameter to fit within the end of the tubular leg and a head part 26 of a diameter equal to the outside diameter of said leg. At the junction of the body and head parts of the plug is an annular shoulder 20 27 and in said body is provided a transverse hole 28. When the plug body is inserted in a tubular leg end, the shoulder 27 will limit said insertion so that the hole 28 in said body will register with the diametrically opposite holes 25 29 in the leg end after which the pintle 19 of the caster is inserted through the registering holes and secured in place, as before describe 1.

The construction, before mentioned, provides 30 a simple and efficient means for providing a finishing cap for a leg end, which cap and leg end act to provide a bearing in which the pintle of the caster is journalled for rotative movement so that the caster can readily 35 trail in the direction of movement imparted to the chair.

While in describing my invention, I have referred to certain details of mechanical construction and form, as well as arrangement of 40 parts, I do not wish to be limited thereto except as may be pointed out in the appended claims.

I claim:

1. In a chair or the like having tubular metallic legs, in combination with one of the 45 legs thereof, means providing a finishing member at and for closing the end of said leg, and a caster frame including a pintle, passing transversely through said chair leg end and a part of said finishing member which 50 are secured together thereby and provide a bearing in which said pintle is journalled.

2. In a chair or the like having tubular metallic legs, in combination with one of the 55 legs thereof having an open end, a finishing member including an end and a body adapted to engage with the open end of said leg to close the same, said leg and body of said finishing member having registering transverse openings therein, and a caster frame including 60 a pintle, journalled in said registering openings and securing said finishing member to said leg.

3. In a chair or the like, in combination with one of the tubular legs thereof having 65 aligned openings therein, a finishing member including a tubular body and a head, which tubular body is adapted to embrace said leg end and is provided with openings adapted to register with said openings in said leg end, 70 and a caster frame including a pintle which extends through and is journalled in said registering openings, and secures said finishing member to said leg end.

4. In combination with the leg of a chair, 75 a cap fitting over the end thereof, said chair leg and cap having registering openings therein, a caster frame including a pintle which extends through said registering openings, said pintle acting to secure the cap to 80 said leg end and said leg end and cap providing a journal bearing for said pintle.

In witness whereof, I have hereunto set my hand this 18th day of July, 1924.

FREDERICK HAGGER HEADLEY.
